UNITED STATES PATENT OFFICE.

HOWARD D. COLMAN, OF ROCKFORD, ILLINOIS, ASSIGNOR TO HOWARD D. COLMAN, LUTHER L. MILLER, AND HARRY A. SEVERSON, COPARTNERS DOING BUSINESS AT ROCKFORD, ILLINOIS, AS BARBER-COLMAN COMPANY.

THREAD-BOARD-CLEANING APPARATUS.

1,114,859.

Specification of Letters Patent.

Patented Oct. 27, 1914.

Application filed December 18, 1911. Serial No. 666,493.

To all whom it may concern:

Be it known that I, HOWARD D. COLMAN, a citizen of the United States, residing at Rockford, in the county of Winnebago and 5 State of Illinois, have invented certain new and useful Improvements in Thread-Board-Cleaning Apparatus, of which the following is a specification.

This invention relates to improvements in 10 the class of apparatus illustrated in application Serial No. 562,431, filed May 20, 1910, by Howard D. Colman and Burt A. Petersen.

The object of this invention is to simplify 15 and otherwise improve the means for driving and reversing the cable which operates the cleaning devices, and to improve the means for guiding the cable.

In the accompanying drawings, Figure 1 20 is a fragmental plan view of a spinning frame provided with apparatus embodying the features of my invention. Fig. 2 is a transverse vertical sectional view taken in the plane of dotted line 2 2 of Fig. 1. Fig. 3 is 25 a fragmental side elevation of the cable-driving and reversing mechanism. Fig. 4 is a sectional view illustrating a portion of said mechanism in a different position than that represented in Fig. 3. Fig. 5 is a top 30 plan view of the parts seen in Fig. 3. Fig. 6 is a detail view illustrating the reversing member and the means for operating said member. Fig. 7 is a fragmental sectional view through the reversing member and an 35 auxiliary means for moving said member. Fig. 8 is a view looking from the right-hand side of Fig. 5. Fig. 9 is a section on line 9 9 of Fig. 3.

In the drawings *a* are the drawing rolls, *b* 40 the thread boards, *c* the thread guides hinged to said thread boards, and *d* the usual pig-tails on the thread guides.

The cleaning apparatus comprises two devices 1 of any suitable character, arranged to 45 be reciprocated upon the thread boards and the thread guides of the spinning frame, one cleaning device being provided for each side of the frame. Said devices are attached to an endless cable 2 which is moved first in 50 one direction and then in the other to traverse the cleaning devices from one end to the other of the thread boards. At the corners of the spinning frame are provided brackets 3 to which are attached cable guides

extending entirely around the cable so as to 55 obviate any possibility of the cable leaving its guides. Herein I have shown the cable guides as consisting of short sections of tube 4 brazed, soldered or otherwise secured to the brackets 3, the tubes being bent so as to 60 guide the cable around the corners. Intermediate the guides at one end of the spinning frame is a bracket 5 supporting a sleeve or short tube 6 through which the cable runs.

The mechanism for driving the cable and 65 for reversing its direction of movement when the cleaning devices have traveled from one end of the thread boards to the other, is supported upon and at one end of the spinning frame. Said mechanism comprises a base 70 plate 7 to which are secured two upwardly extending brackets 8 and 9. In these brackets is mounted a shaft 10 having fixed to one of its ends a sheave 11 having therein a plurality of annular grooves to receive the cable 75 2. Proper tension is maintained in the cable by extending a loop of the cable downward from the sheave 11 through openings 12, and supporting in said loop a weighted take-up sheave 13. The means for rotating the shaft 80 10 comprises a wheel 14 fixed upon said shaft and having square peripheral teeth 15. These teeth are engaged by a pawl pivoted upon an arm 16, said arm being fast to a sleeve 17 surrounding the shaft 10. The 85 sleeve 17 is mounted in a bearing opening in the bracket 8. The arm 16 is swung by means of an arm 18 secured to the sleeve 17 and connected by a link 19 to a crank arm 20 fixed to one of the drawing rolls *a*. The 90 pawl consists of two oppositely extending fingers 21 and 22, each adapted to engage the teeth 15. A spring 23 fixed to the arm 16 at 24 and to a finger 25 upon the pawl at 26 tends to hold either finger in operative 95 position.

The means for shifting the pawl to bring its fingers 21 and 22 alternately into operative position comprises a three-arm member 27 fixed to a sleeve 28 (Fig. 7) which is 100 loosely mounted on a pin 29 projecting from the bracket 9. The middle arm 30 of the reversing member 27 is arranged for engagement by a stud 31 fixed to a spur gear wheel 32 which is loosely mounted upon the 105 shaft 10. Said spur gear meshes with a pinion 33 formed upon or otherwise suitably secured to a shaft 34, to which shaft is fixed

a spur gear 35 meshing with a pinion 36 formed in or attached to the shaft 10. The arms 37 and 38 of the reversing member 27 have angular ends adapted alternately to engage a projection 39 (Fig. 8) upon the finger 25. A member 40 having notches 41 and 42 therein is formed upon the sleeve 28. These notches are adapted to receive a wedge-shape tooth 43 formed upon a lever 44 pivoted at 45 and acted upon by a tension spring 46.

Assuming the parts to be in the position shown in Figs. 3 and 6, the operation is as follows: Each rotation of the crank 20 produces an oscillation of the arm 16, each such oscillation causing a feeding movement and a restoring movement of the pawl finger 21. The intermittent movement thus imparted to the toothed wheel 14 causes the stud 31 to swing the arm 30 until the point of the tooth 43 has left the notch 41 and is about to enter the notch 42, when the pressure of said tooth causes the reversing member 27 to swing into the position shown in Fig. 4. The arm 37 of the reversing member is thereby placed in the path of the projection 39 upon the pawl so that continued movement of the arm 16 to the left (Fig. 4) causes the pivot of the pawl to pass to the opposite side of a straight line joining the points 24 and 26, whereupon the spring 23 turns the pawl to throw the finger 22 into operative position. The direction of rotation of the toothed wheel 14 is thereby reversed, with a consequent change in the direction of travel of the cleaning devices 1. The length of movement of the stud 31 is so proportioned to the length of the thread-boards that the reversing member 27 is swung from one of its positions to the other when the cleaning devices reach the end of the thread boards.

I claim as my invention:

1. In thread-board cleaning apparatus, a cleaning device, a cable for moving said device, a sheave engaging said cable, a toothed wheel connected to drive said sheave, an oscillatory arm adjacent to said wheel, means for oscillating said arm, a double pawl pivoted on said arm, an oscillatory member arranged to swing opposite portions of said pawl alternately into engagement with said toothed wheel, and a traveling member arranged to periodically engage and swing said oscillatory member to reverse said pawl.

2. In thread-board cleaning apparatus, a cleaning device, a cable for moving said device, a sheave engaging said cable, a toothed wheel for rotating said sheave, a pawl comprising two oppositely extending fingers each adapted to engage said toothed wheel, means for rocking said pawl to move said fingers into and out of operative relation with the toothed wheel, said rocking means comprising a three arm member, two arms

of which member are arranged to operate said pawl, and means actuated in the movement of said sheave for operating the other arm of said reversing member.

3. In thread-board cleaning apparatus, a cleaning device, a cable for moving said device, a wheel engaging said cable, a toothed wheel for rotating said other wheel, two pawl fingers each adapted to engage said toothed wheel, means for actuating said fingers and means for moving said fingers into and out of operative relation to said toothed wheel comprising a member arranged to control said fingers, said member having an arm, and a pin revolving with said cable-engaging wheel and arranged to move said arm.

4. In thread-board cleaning apparatus, a cleaning device, a cable for moving said device, a sheave engaging said cable, a toothed wheel for rotating said sheave, a pivoted arm, means for oscillating said arm, a double pawl pivoted on said arm arranged to engage said toothed wheel, a spring adapted to rock said pawl in either direction upon its pivot, and pawl-shifting means comprising a pivoted member having two arms each adapted to obstruct the movement of said pawl whereby continued movement of said arm causes said pawl to move into position where said spring can shift the pawl with relation to the toothed wheel.

5. In thread-board cleaning apparatus, a cleaning device, a cable for moving said device, a sheave engaging said cable, a toothed arm, means for oscillating said arm, a double pawl pivoted on said arm arranged to engage said toothed wheel, a spring adapted to rock said pawl in either direction upon its pivot, pawl shifting means comprising a pivoted member having two arms each adapted to obstruct the movement of said pawl whereby continued movement of said arm causes said pawl to move into position where said spring can shift the pawl with relation to the toothed wheel, a central finger on said double pawl to which finger one end of said spring is attached, and automatically-actuated means for shifting said pawl comprising a member having two arms each adapted to lie in the path of said central finger whereby continued movement of said arm causes the pawl pivot to move from one side to the other of a straight line joining the points of attachment of said spring whereby the latter is enabled to shift the pawl.

6. The combination with a spinning frame, of thread-board cleaning devices, a cable to which said devices are attached, a cable driving and reversing means attached to the spinning frame at one end of the latter, a crank arm attached to one of the drawing rolls, and a link connecting said crank arm to said cable driving and reversing means.

7. In thread-board cleaning apparatus, a cleaning device, a cable for moving said device, a rotary shaft, a sheave fixed on said shaft, a toothed wheel fixed on said shaft, an oscillatory arm adjacent to said wheel, a double pawl mounted on said arm and engaging said wheel, means for swinging said arm, a member arranged to engage said pawl to reverse it, and means driven by said shaft for engaging and moving said member.
8. In thread-board cleaning apparatus, a cleaning device, a cable for moving said device, a sheave engaging said cable, a toothed wheel connected to drive said sheave, driving means including a double pawl engaging a toothed wheel, a member arranged to engage said pawl to reverse it, a rotary member having an operative connection with said sheave, and a projection on said member arranged to engage and operate said pawl-reversing member.
9. In thread-board cleaning apparatus, a cleaning device, a cable for moving said device, a sheave engaging said cable, means for driving said sheave including a toothed wheel and a double pawl engaging said wheel, and means for reversing said pawl including a rotary wheel geared to said
- sheave and having an operating projection 30 timed according to the length of travel of said cleaning device.
10. In thread-board cleaning apparatus, a cleaning device, a cable for moving said device, a sheave for moving said cable, means 35 for driving said sheave including a toothed wheel and a double pawl engaging said wheel, and means for reversing said pawl including a revolute part having an operating connection with said sheave and timed 40 in its movement to reverse the pawl when said cleaning device reaches the ends of its travel.
11. The combination of a spinning frame, a thread-board cleaning device, a cable to 45 which said device is attached, a sheave engaging said cable, a crank arm attached to one of the drawing rolls, a second crank arm, a link connecting said crank arms, and a driving and reversing mechanism operatively connecting the second mentioned 50 crank arm with said sheave.

In testimony whereof I hereto affix my signature in presence of two witnesses.

HOWARD D. COLMAN.
